UNITED STATES PATENT OFFICE.

WILLIAM B. BANDY, OF CROSSVILLE, TENNESSEE, ASSIGNOR OF FORTY-NINE ONE-HUNDREDTHS TO WILLIAM H. JACKSON, OF CROSSVILLE, TENNESSEE.

WRENCH.

1,368,380.

Specification of Letters Patent. Patented Feb. 15, 1921.

Application filed January 29, 1920. Serial No. 354,929.

To all whom it may concern:

Be it known that I, WILLIAM B. BANDY, a citizen of the United States, residing at Crossville, in the county of Cumberland and State of Tennessee, have invented certain new and useful Improvements in Wrenches, of which the following is a specification, reference being had to the accompanying drawings.

This invention relates to wrenches and has for its object to provide a device of this character which adjusts itself when applied to the work.

Another object is to provide a wrench of this character including a pair of pivoted jaws carried by a handle, one of said jaws being arranged for oscillating movement and the other for sliding movement.

Another object is to provide a wrench of this character including a pair of jaws pivoted to each other at their intermediate portion, the adjacent edges of each jaw on both sides of the pivotal connection coöperating to form gripping jaws.

Another object is to provide a wrench of this character having a nut threaded on the handle and adapted to engage the end of the adjustable jaw, to hold the wrench adjusted.

With these and other objects in view the invention consists in the improved construction and improvement of parts to be herein-after more particularly described, fully claimed and illustrated in the accompanying drawings in which:

Figure 1 is a side elevation of a wrench constructed in accordance with one form of my invention;

Fig. 2 is a top plan view of the wrench shown in Fig. 1, partly broken away;

Fig. 3 is an under side plan view;

Fig. 4 is a section on the line 4—4 of Fig. 1;

Referring to drawing 5 designates a handle having its edges 6 threaded and its end 7 reduced to provide an extension 8. The end 7 is provided with a slot 9 which extends longitudinally of the handle and through the sides 10.

Associated with the handle, is a pair of jaws 11 and 12, the jaw 11 having its ends and intermediate portions furcated to provide arms 13. The end portion 14 of each arm, extends upwardly in angular relation to the arm and has its extremity 15 extending in angular relation to the portion 14.

The surface 16 of the extremity 15 and the surface 17 of the portions 14 are provided with gripping teeth. A V shaped recess 18 is formed in the side edges of the arms 13 remote from the edges containing the gripping teeth, and at the junction of the end portion 14 with the arm, to provide wire cutting means and also an additional gripping surface through the coöperation of the adjacent edges of the end of the jaw 12, each arm being provided with a pivot opening 19. The intermediate furcated portion of the jaw 11 is intended to receive the shank 20 of the jaw 12, the intermediate portion of the shank 20 is provided with an opening 70 which registers with the openings 19, a pin 22 being passed through the registering openings. The end portion 23 of the jaw 12 includes extensions 24 on each side thereof, which terminate adjacent the end 25 of the shank 20. The end 25 together with a portion of the extensions 24 extends in angular relation to the shank 20, the angularly extended portion and the adjacent portion of the shank being provided with gripping 80 teeth. The ends of the extensions are intended to engage the side edges of the jaw 11 to limit movement of the jaw 12 toward and away from the jaw 11, the end 25 of the jaw 12 being received in the furcated 85 end portion of the jaw 11.

The end 26 of the jaw 12 is furcated and adapted to receive the extension 8 of the handle 5, a pivot pin 27 being passed through the end 26 and handle to pivot the 90 jaw to the handle. The threaded end of the handle 5 is intended to be received in the furcation of the ends 28 of the arms 13. A pin 29 is provided to connect the ends 28 of the arms 13, the intermediate portion of the pin 29 being slidably disposed in the slot 9 of the handle. When the jaws are thus connected to the handle, the portion of the shank 20 of the jaw 12 adjacent the end 26 thereof coöperates with the 100 groove 18 to provide additional gripping surfaces so that two wrenches are provided by the novel arrangement of one pair of jaws.

A manually operable nut 30 is rotatably 105 mounted on the threaded end 7 of the handle, stops 31 being provided at the end of the threaded portion to prevent disengagement of the nut 30 from the handle. This nut is rotated on the end 7 into engagement 110

with the ends 28 of the arms 13 to adjust the jaws to the size desired. In use, the nut 30 is rotated on the handle so as to move the jaw 11 toward the end of the handle and the jaw 12, and through said movement cause the jaw 12 to move toward the jaw 11 and engage the work. The wrench is used in the usual manner and the same operation occurs when the work is engaged by the toothed recess 18. The nut 30 may be adjusted to cause the jaws to engage the work but not bind thereon. In this way, the wrench may be used similarly to a ratchet lever, that is, without requiring the handle of the wrench to revolve with the work but to revolve the work step by step.

From the foregoing it will be readily seen that this invention provides a novel form 20 of wrench containing two separate gripping surfaces, one of which may be used for the purpose of holding or cutting wire. In addition to the self-adjusting feature, the wrench is provided with a nut for holding 25 the jaws adjusted or for permitting the instantaneous self-adjustment of the jaws on small work, and all of these features are possessed by a wrench that is simple in construction. If desired, another method may 30 be used in adjusting the wrench and consists of placing the jaws into engagement with the work and moving the lever to one side so as to cause the jaws to firmly engage 35 the work. The nut 30 may then be rotated on the handle into firm engagement with the end 28 of the jaw 11. It will thus be seen that in addition to its various uses, the wrench is also capable of being adjusted by several methods.

40 What is claimed is:

1. A wrench of the character described comprising a handle having a slot adjacent one end, a substantially L-shaped oscillating jaw and a substantially Z-shaped sliding jaw, said oscillating jaw being pivoted at one end to the handle adjacent the slot,

the other end portion of said jaw having opposed extensions on its sides, said sliding jaw being slotted from its intermediate portion through one end and adapted to 50 straddle the oscillating jaw, said jaws being pivoted to each other at the intermediate portions, the slotted end of the sliding jaw being arranged to straddle the end portion of the handle over the slot therein, a 55 pin extending through said slot and the handle, the ends of the extensions of the oscillating jaw being arranged to alternately engage the end and intermediate portion of the sliding jaw to limit movement 60 thereof.

2. A wrench of the character described comprising a handle, there being a slot extending laterally of the handle, a portion of the handle adjacent the slot being 65 threaded, an oscillating jaw and a slideable jaw, said oscillating jaw being pivoted at one end to the handle and having the rear face thereof adjacent its pivotal connection reduced, said slideable jaw having its end 70 portions extending in the opposite direction to each other and provided with a recess at the junction of one of said end portions with the intermediate portion of the jaw, said intermediate and end portions being longitudinally slotted, said slideable jaw being arranged to straddle the oscillating jaw at its intermediate portion, said end of the slideable jaw being movable over the slotted portion of the handle, the recess in 80 the slideable jaw coöperating with the reduced portion adjacent the pivotal connection of the oscillating jaw to the handle to provide additional gripping surfaces, and an internally threaded member rotatable on 85 the handle for engagement with the threads thereof and adapted to operatively engage the end of the slideable jaw to gradually adjust said jaws upon movement of said member in one direction.

WILLIAM B. BANDY.
